UNITED STATES PATENT OFFICE.

ARTHUR MIDDLETON ROSE, OF YONKERS, NEW YORK, ASSIGNOR TO
MATTHEW J. WHITTALL, OF WORCESTER, MASSACHUSETTS.

DESIGN FOR CARPET.

SPECIFICATION forming part of Design No. 24,100, dated March 12, 1895.

Application filed December 15, 1894. Serial No. 531,981. Term of patent 3½ years.

To all whom it may concern:

Be it known that I, ARTHUR MIDDLETON ROSE, of Yonkers, county of Westchester, and State of New York, have invented a new and original Design for Carpets, of which the following is a specification, reference being had to the accompanying drawing, which forms a part of the same.

My invention relates to a design to be worked into or upon surfaces, such as carpeting or similar fabrics, and it consists of the novel features and arrangements as herein described and claimed.

The accompanying drawing is a face view of a carpet embodying my new design.

The drawing illustrates a body and a border.

The body A consists of a groundwork upon which are disposed in an irregular manner sprays or clusters of conventionalized flowers and leaves. The flowers are patterned from the blossom of the holly-hock, and the sprays

or clusters are arranged to present an open appearance.

The border B consists essentially of a 25 groundwork and a longitudinal figure, which extend substantially parallel with the sides of the border, said figure being arranged so as to leave a considerable section or panel of the groundwork exposed upon each side 30 thereof. The longitudinal figure consists of a longitudinally extending conventionalized figure, spray or vine, which will harmonize with the body of the carpet in connection with which the border is to be used.

What I claim as new, and desire to secure by Letters Patent, is—

The design for carpeting consisting of the body and the border, substantially as shown and described.

ARTHUR MIDDLETON ROSE.
